DESIGN FOR AN EYE MASSAGING DEVICE

Sasha R. Grossman, New York, N. Y.

Application January 5, 1934, Serial No. 50,326

Term of patent 7 years

To all whom it may concern:

Be it known that I, SASHA R. GROSSMAN, a citizen of the United States, residing at New York city, in the county and State of New York, have invented a new, original, and ornamental Design for an Eye Massaging Device, of which the following is a specification; reference being had to the accompanying drawing, forming part thereof.

Fig. 1 is a plan view of an eye massaging device, showing my new design.

Fig. 2 is a front elevation thereof, and
Fig. 3 is an end view of the same.

I claim:

The ornamental design for an eye massaging device, as shown.

SASHA R. GROSSMAN.
